UNITED STATES PATENT OFFICE

2,535,496

WINDOW CONSTRUCTION

Roy G. Johnson, Moline, Ill., assignor of one-half
to August Altieri, Washington, D. C.

Application November 1, 1944, Serial No. 561,399

5 Claims. (Cl. 160—182)

1

The present invention relates to building structures and more particularly to means for weather proofing and holding windows, storm sash and screens in openings in said structures.

It is an object of the present invention to provide means in openings in a building structure that will permit screens, storm sash and windows to be positioned in the openings from the inside of a building.

Another object of the present invention is the provision of means for positioning sash, screens and storm sash in openings in old or new structures.

A still further object of the present invention is the provision of means for weather proofing the openings in buildings.

A still further object of the present invention is the provision of means for mounting sash, screens and storm sash in old openings without the necessity of remodeling said openings.

Other objects of the present invention will be more apparent from the description and claims when taken in conjunction with the accompanying drawings in which:

Figure 1 is an isometric view of a window opening, parts being broken and in section, and illustrating the various elements assembled in the opening.

Figure 2 is a broken vertical sectional view of a window opening and illustrating the relative position of the various elements.

Figure 3 is a partial horizontal sectional view of a window opening and illustrating the side jamb liner with parts shown fragmentarily.

Figure 4 is a perspective view of the head jamb liner and the top sash rail liner, portions being shown fragmentarily.

Figure 5 is a reduced broken sectional view of window sash showing screen material therein.

The opening in a building as referred to herein, is a window opening represented by the numeral 10, and within the opening at the bottom, sides and top are elements well known in the art. It is deemed advisable for a clear understanding of the present invention that these elements be referenced.

At the bottom of the opening the numeral 11 represents a sleeper sill, 12 lath, 13 plaster, 14 inside trim, 15 inside window stool, 16 outside sheathing, 17 window sill, 18 a sill plate and 19 an alining wedge.

The elements that make up the side of the window frame comprise the side jamb 20, having an opening 21 where a parting strip is normally positioned, a stud 22, a binder strip 23, outside

2

casing strip 24, lath 25, plaster 26 and inside casing trim 27.

5 A metal sill 28 is positioned in the opening 10 and it is provided with a channeled portion 29, the sill being secured by any suitable means. As shown in the drawings an alining wedge 19 is positioned in the opening, the metal sill resting thereon. The side walls 30 and 31 of the metal sill 28 are disposed at an inclined angle, the channel portion 29 serving a purpose to be later described.

10 To the side jamb 20 there is mounted a metal side jamb liner 32 of integral hollow structure and having one end 33 of oblong configuration and provided with an abutment 34 and a smaller abutment 35, the opposite end 36 of the liner 32 being deformed and provided with a tongue 37 and an abutment 38, the tongue 37 serving a purpose to be later described. The side jamb liner 32 is secured to the side jamb by screws 39.

15 Secured to the head jamb 40 by screws 41 is a head jamb liner 42, having one end 43 of substantially rectangular configuration and having an abutment 44 and a smaller abutment 45, the opposite end of the liner 42 being provided with a channel 46 and a U-shaped portion 47 having a ridge portion 48 and a flange 49 that is provided with apertures 50 that receive screws 51 that engage the head jamb and secure the jamb liner 42 thereto.

20 Within the opening 10 there is mounted as a unit a sash 52 that comprises side sash stiles 53 having a rabbed portion 54, a top rail 55, a transverse rail 56 and a bottom rail 57. To the sash stile 53 there is secured by any suitable means such as by screws 58 a stile liner plate 59 that is provided with a channeled portion 60 that is adapted to engage the tongue portion 37 of the side jamb liner 20, the abutment 61 engaging the abutment 38 as shown in Figures 1 and 3.

25 The top rail 55 is provided with an irregular rabbed portion 62 that receives a liner plate 63 formed to engage the irregular rabbed portion 62. It is to be noted that the liner plate 63 is provided with abutments 64 and 65, and the abutment 65 extending below the abutment 64. The liner plate is provided with a ridge 66 that is adapted to engage the channel 46 for a purpose to be later described. The bottom sash rail 57 is rabbed and it receives a sash rail liner 67 that may be secured thereto by any suitable means. The rail liner 67 is provided with angularly disposed walls 68 and 69 that are adapted to engage the walls 30 and 31 on the sill liner 28, the ridge 70 on the liner adapted to engage

the channel 29. The transverse rail 56 is provided with a stepped rabbeted portion 71 and the bottom rail with a stepped rabbeted portion 72 both for a purpose to be later described.

The transverse rail 56 divides the unit sash 52 into an upper portion 73 and a lower portion 74. The lower portion 74 receives a sash 75 having side rails 76, a top rail 77 and a bottom rail 78. The side rails 76 are provided with stepped rabbeted portions 79 that engage companion rabbeted portions 80 in the side sash stiles 53. The top rail 77 is provided with a stepped rabbeted portion 81 that engages the stepped rabbeted portion 71 in the transverse rail 56. The bottom rail 78 is provided with a stepped rabbeted portion 83 that engages the rabbeted portion 84 in the bottom rail 57. The sash 75 is hingedly mounted to the rail 57 by hinges 85. Any suitable means may be used for holding the window or sash 75 in an inclined open position, such as by a chain 86 shown by dotted lines in Figure 2.

In Figures 1 and 2 I have shown a storm sash but I would have it distinctly understood that the same structure as shown on the storm sash would be shown on a screen. As shown in Figures 1, 2, and 3 the storm sash 87 is positioned in the opening 10 and it is provided with a rabbeted portion 88 that engages the abutment 34 of the element 32, the top rail 89 being provided with a rabbeted portion 90 that engages the abutment 44 in the head jamb liner 42. The storm sash or screen are secured in the opening by bolts 91 as shown by dotted lines in Figure 2. The sash 73, the sash 74 and the storm sash 87 are provided with glass panes 92, 93 and 94. The sash 73 and 74 may be provided with screen 92' and 93' as shown in Figure 5.

In the application of my device to an opening in a building, if the building is old, the only alteration that is necessary is the removal of the parting strips from the opening 21. If the opening is new construction obviously it is only necessary to build the framing without the parting strips. The metal sill 28 is positioned in the opening and it is superposed upon the alining wedge 19. The side jamb liners 32 are then positioned in the opening and they are secured in place by screws 39. The head jamb liner 42 is then positioned in the opening and it is secured in place by the screws 41 and 51.

The unit sash 52 is inserted in the opening 10 and during the insertion the following takes place. The ridge 66 is brought into alinement with the channel 46 and when so alined is pushed upwardly, the ridge 66 entering the channel 46 and at this point the ridge 70 is brought into alinement with the channel 29 and when so alined is pushed downwardly, the ridge 70 snugly engaging the channel 29, the walls 68 and 69 engaging the walls 30 and 31 of the sill 28. During the alining of the unit 52, the abutment 61 engages the abutment 38, the tongue 37 engaging the channel 60 snugly, thus providing a securing means for holding the unit in the opening 10 and at the same time providing weather-proofing around the unit and opening. It is to be noted, as shown in Figure 2 of the drawings that the ridge portion 66 has one face 95 that is in lapped engagement with the face 96 of the U-shaped portion 47 thus providing weather-proofing at the top of the opening.

From the description and drawings it can be seen that my novel construction provides means whereby storm sash, screens and an inside window may be placed in an opening in a building

without the necessity of going to the exterior of the building, they may be put in place from the inside of a building. When the storm sash and window unit are in position the opening or openings are absolutely sealed against the winter elements, the structure providing a complete seal around the opening and unit.

What I claim is:

1. In a wall having a window opening, a frame comprising a metal head liner, metal side jamb liners, an alining wedge member for the sill of the window opening and a hollow metal sill on said member flush with the inside window stool of said opening, said sill having a groove in the top which top slopes downwardly away from said groove edges, a deeper groove in the bottom of the head liner, the side jamb liners having a tongue extending from their inner edges spaced from the sides of the window opening, the outer edges of said liners having inner and outer abutments, said outer abutments fitting in the outer corner of the window opening, a closure element fitted against the sill of the window opening and the inner abutment around the outer edges of the liners, means for locking said closure element in place, a window sash with metal lined flanges at the top and bottom and metal sash stile liners on the sides extending around the outer edge of the stiles to form a groove in register with the tongues of the side jamb liners thus forming weather stripping means around the sides, the metal lined flanges of the window sash fitting in the head liner groove and the sill groove, thus completing the weather stripping around the top and bottom.

2. A window structure in a wall having a rectangular opening, comprising: a frame within said opening having abutment means extending inwardly of said opening near the outer edge of said frame, outer closure means fitting against the inner edge of said abutment means, means for locking said outer closure means in place, operable from the inside, grooves in the top and bottom of said frame near its inner edge, said upper groove being deeper than the lower one, inner closure means having flanges at the top and bottom for insertion in the corresponding grooves in said frame, said upper flange having a clearance in said deeper groove for removal and replacement of the lower flange in its groove without dropping said upper flange out of its groove.

3. A window structure in a wall having a rectangular opening, comprising: a frame within said opening having abutment means extending inwardly of said opening near the outer edge of said frame, a storm sash fitting against the inner edge of said abutment means, said storm sash being rabbeted to conform with said abutment means, means for locking said storm sash in place, groove means near the inner edges in the top and bottom of said frame, a window sash in said frame, flange means on the top and bottom of said window sash registering with said groove means, said upper groove and flange means having a clearance for insertion and removal of said lower flange in its groove without dropping said upper flange out of its groove.

4. In a wall having a window opening, a frame comprising a hollow metal head liner, hollow metal side jamb liners, an alining wedge member for the sill of the window opening, and a hollow metal sill on said member flush with the inside window stool of said opening, said sill having a groove in the top which top slopes down-

wardly away from said groove edges, a deeper groove in the bottom of the head liner, the side jamb liners having a tongue extending from their inner edges spaced from the sides of the window opening, the outer edges of said liners having inner and outer abutments, said abutments fitting in the outer corner of the window opening, a storm sash fitted against the sill of the window opening and the inner abutment around the outer edges of the liners, means for locking said storm sash in place, a window sash with metal lined flanges at the top and bottom and metal sash stile liners on the sides extending around the outer edge of the stile to form a groove in register with the tongues of the side jamb liners to form weather stripping means around the sides, the metal lined flanges of the window sash fitting in the head liner groove and in the sill groove, thus completing the weather stripping around the top and bottom.

5. In a wall having a window opening, a frame comprising a hollow metal head liner, hollow metal side jamb liners, an alining wedge member for the sill of the window opening, and a hollow metal sill on said member flush with the inside window stool of said opening, said sill having a groove in the top sloping downwardly away from said groove edges, a deeper groove in the bottom of the head liner, the side jamb liners each having a tongue extending from its inner edge spaced from the sides of the window opening, the outer edges of said liners having inner and outer abutments, said outer abutments fitting in the nor-

mally rabetted outer corner of the window opening, a screen insertable from inside the wall against the sill of the window opening and the inner abutment around the outer edges of the liners, means for locking said screen in place, a window sash with metal lined flanges at the top and bottom and metal sash stile liners on the sides extending around the outer edge of the stile and provided with a groove for registration with the tongues of the side jamb liners to form weather stripping means around the sides, the window sash being readily installable by slipping the upper flange all the way into the head jamb liner groove and then dropping the lower flange into the sill groove, thus completing the weather stripping around the top and bottom.
